UNITED STATES PATENT OFFICE

2,508,837

SETTING-UP INSTRUMENT

Ira W. Peffers, Newark, Ohio

Application April 7, 1947, Serial No. 739,865

1 Claim. (Cl. 33—174)

1

This invention relates to a setting up instrument for precision machine work and has for its primary object to enable a machine operator who is not versed in trigonometry easily and quickly to set up work in a machine.

Another object is to conserve time in setting up precision machine work.

The above and other objects may be attained by employing this invention which embodies a plate having a reference opening therein, said plate also having an arcuate row of openings in concentric spaced relation to the reference opening, the openings in said row being spaced from one another a known number of degrees with relation to the reference opening, a stop adapted to be entered into the reference opening and a second stop selectively to enter an opening in the row of openings, whereby a straight edge laid on the plate against the stops will lie along a known angle.

Other features include heads on the stops having eccentric peripheries which may be rotated to change the angle of the straight edge in minutes and seconds.

Still other features includes indices on the heads by which the minutes and seconds may be known to the user.

In the drawings, Figure 1 is a side view of a setting up instrument embodying the features of this invention.

Figure 2 is a view similar to Figure 1 showing the instrument turned on end.

Figure 3 is a sectional view taken substantially along the line 3—3 of Figure 1.

Figure 4 is a sectional view taken substantially along the line 4—4 of Figure 1.

Figure 5 is a sectional view taken substantially along the line 5—5 of Figure 1.

Figure 6 is a plan view of one of the stops.

Figure 7 is a view similar to Figure 6 of a co-operating stop, and

Figure 8 is a side view of the stop illustrated in Figure 7.

Referring to the drawings in detail, an angle plate designated generally 10 comprises legs 11 and 12 which extend perpendicular to one another. The bottom edge 13 and an end edge 14 of the angle plate are smooth, true and accurate to extend perpendicular to one another and form working surfaces for the device. Extending through the leg 12 near the lower left hand corner thereof is a row of spaced apertures 15 the axes of which lie in a plane parallel with the finished edge 13 of the plate and scribed on the outer exposed face of the plate in alignment

2

with the axes of the apertures are center lines 16 which extend perpendicular to the longitudinal axis of the row of apertures. These apertures 15 are spaced from one another a uniform distance and form reference openings for the reception of a stop to be more fully hereinafter described.

Scribed on the outer face of the plate near the edge 14 thereof and in concentric relation with their respective apertures 15 are center lines 17 and formed in the plate at spaced intervals along each center line 17 are apertures 18. As illustrated, there are five reference openings, and five rows of apertures 18 with the lowermost aperture 18 of the outermost row centered on the axis which extends through the row of apertures 15 and the other apertures 18 in the outermost row spaced from one another five degrees. The lowermost aperture in the next adjacent row is one degree above the axis of the row of apertures 15, and the succeeding apertures in the next adjacent row are located five degrees apart. The middle arcuate row of apertures starts with the lowermost aperture two degrees above the axis of the row of apertures 15 and the succeeding apertures in said middle row are likewise spaced five degrees apart. The same spacing is preserved in the next succeeding rows with the lowermost apertures respectively thereof spaced three degrees and four degrees above the axis of the row of apertures 15. It will thus be seen that provision is made for measuring a total of forty-five degrees.

A stop designated 19 is provided and comprises a shank or stem 20 provided at one end with an externally screw-threaded extension 21 upon which a wing nut 22 is adapted to be threaded. The end of the stop opposite the threaded extension 21 is provided with a head 23 the periphery 24 of which is eccentric as illustrated in Figures 1, 2 and 7 so as gradually to rise from a low point to a high point substantially 360 degrees about the circumference of the head. An annular series of indices 25 are marked on the outer face of the head to correspond with the rise thereof in seconds. The shank 20 of the stop 19 is adapted to be received in one of the openings 15 to form a reference point as will be readily understood upon reference to the drawings.

A stop designated generally 26 comprising a shank which is adapted to enter one of the openings 18 is also provided and the shank of this stop is provided with a screw-threaded extension for cooperation with a wing-nut 27. A head 28 is formed at the end of the stop opposite the screw-threaded extension and like the head 23 is pro-

vided with an eccentric periphery 29 and indices 30 for indicating the minutes of rise as the stop is rotated in its respective aperture.

In use, the reference stop 19 is introduced into an aperture selected from the group of apertures 15, and the stop 26 is introduced into the aperture 18 corresponding to the number of degrees of angularity desired, and in the row corresponding to the row in which the reference stop is mounted. By laying a straight edge across the stops the rough approximation of the angle desired will be obtained. By rotating the stop 26 until an index mark is over the center line 17 of the row in which the stop is located, the degrees and minutes of the angle may be established. Where it is desired to measure the angle down to seconds, the stop 19 is rotated to bring the desired number of seconds as shown by the indices thereon into alignment with a mark on the straight edge which extends perpendicular to the edge contacting the stops. By way of example, for instance, the reading of the device in Figure 1 is as follows: 32 degrees, 7 minutes and 15 seconds so that by laying a straight edge across the stops the angle when measured from the base 13 will be as stated above. Obviously, by moving the stop 26 to a different aperture 18, the degree of angle will be altered and likewise when the stops 19 and 26 are rotated in their respective openings, the angle will also be altered. In order to assure accuracy, it is of course necessary that the reference stop 19 be mounted in an opening 15 which corresponds to the number of the row in which the stop 26 is fitted.

By the use of this device, it is obvious that a vast number of angles may easily and quickly be laid out simply by positioning the stops in their proper places and laying a straight edge across the stops, with the minutes and seconds obtainable by the simple rotation of the stops in their respective openings.

While in the foregoing there has been shown and described the preferred embodiment of this

invention it is to be understood that minor changes in the details of construction, combination and arrangement of parts may be resorted to without departing from the spirit and scope of the invention as claimed.

5 I claim:

A setting up instrument for precision machine work comprising a plate having a row of spaced reference openings lying parallel with one edge, 10 said plate also having an arcuate row of spaced openings concentric with each reference opening, the openings in each arcuate row being spaced five degrees apart with relation to its respective reference opening and the openings in succeeding 15 arcuate rows being spaced one degree apart, a stop removably supported in an opening in the row of arcuate openings which lies concentric with relation to the reference opening in which another stop is supported, a head on each stop having an 20 eccentric periphery whereby a straight edge resting on the plate against the heads will lie substantially at a known angle, indices on the plate adjacent the rows of openings, and indices on the heads cooperating with those on the plate in 25 indicating in minutes and seconds the position of the straight edge relative to the known angle.
